UNITED STATES PATENT OFFICE.

D'ALTON TOPLIFF, OF FRANKLIN, ILLINOIS.

BUGGY-IRON.

SPECIFICATION forming part of Letters Patent No. 349,128, dated September 14, 1886.

Application filed February 15, 1886. Serial No. 191,955. (No model.)

To all whom it may concern:

Be it known that I, D'ALTON TOPLIFF, of Franklin, in the county of Morgan and State of Illinois, have invented a new and useful 5 Improvement in Buggy-Irons, of which the following is a specification, reference being had to the annexed drawings, forming a part thereof, in which—

Figure 1 is a side elevation of a buggy-body, 10 showing the application of my improvement. Fig. 2 is a vertical transverse section taken on line $x-x$ in Fig. 1. Fig. 3 is a detail perspective view of the iron attached to the buggy-sill. Fig. 4 is a sectional view of a modified form of the iron. Fig. 5 is a perspective view of the same.

Similar letters of reference indicate corresponding parts in the different figures of the drawings.

20 In buggy-bodies having deep sides, as commonly constructed, the side panels are liable to be split at their ends, near their upper corners, by the weight of the load applied to the middle of the body, the sills being allowed 25 to spring, while the sides of the body, being deep, are incapable of springing. To obviate this difficulty I provide an angled iron, which I attach to the sills near their ends and extend under the edges of the panels of the body to 30 sustain the ends of the panels. The buggy-body A is of the usual description, having the side panels, B, and end boards, C, (shown in dotted lines in Fig. 1,) and having the sills D extending along the inner side of the panels B 35 at the bottom of the body.

My improved iron consists of a plate, E, bent twice approximately at right angles, or offset, as shown in Figs. 2 and 3, the upper horizontal part, a, of the plate resting on the 40 top of the sill D, the vertical part b extending down the side of the sill D, and the lower horizontal part, c, projecting outward under the edge of the panel B. The plate E is provided with screw-holes in both the upper and lower

part, and is secured to the sill by screws passing through it into the sill, and the edge of the panel B, which rests upon the part c, is also secured to the plate E by screws passing through the plate into the edge of the panel.

When it is desired to apply my improvement to the back board, as well as to the side panel of the buggy-body, I provide an angled plate, E', which is formed on a right angle and adapted to embrace the side and end of the sill D, and to receive on the lower horizontal part, c, the edges of the panel and of the end board. The panel is sustained by the plates E E', so that when weight is applied to the center of the panel it will be supported from its lower edges, instead of the points of attachment to the corner posts of the buggy-body. In this way the strain will be removed from the fastenings of the panel and will be transferred to the irons E E'.

Having thus described my invention, what I claim as new, and desire to secure by Letters Patent, is—

1. The combination, with the buggy-body B, having the transverse sills D within it at opposite ends, of the double-angled irons E, having their vertical arms b extended up between the ends of the buggy-body and the sills, the upper horizontal parts resting on top of the sills, and the lower parts resting against the lower edges of the body ends, as shown and 75 described.

2. The combination, with a sill, D, and panel B of a buggy-body, of an iron formed of a plate, E, bent twice approximately at right angles, or offset, and adapted to rest on the sill 80 of the body and to support the lower edge of the panel, substantially as herein shown and described.

D'ALTON TOPLIFF.
